INVENTOR;

Wm. W. St. John

UNITED STATES PATENT OFFICE.

WM. W. ST. JOHN, OF LIMA, NEW YORK.

ATTACHING SLEIGH-RUNNERS.

Specification of Letters Patent No. 20,903, dated July 13, 1858.

To all whom it may concern:

Be it known that I, WILLIAM W. ST. JOHN, of Lima, in the county of Livingston and State of New York, have invented, 5 made, and applied to use a certain new and useful Improvement in Attaching Sleigh-Runners to the Bodies of Sleighs; and I do hereby declare that the following is a full, clear, and exact description of the construction and operation of the same, reference being had to the annexed drawing, 10 making part of this specification, wherein—

Figure 1, is a side elevation of the runners and bolsters and Fig. 2, is an elevation of 15 the back part of the hind runner with my improved bolsters.

Similar marks of reference indicate the same parts.

My invention is applicable to sleighs having 20 two pairs of runners, and in this character of sleigh it is well known that independent motions must be allowed to each pair of runners to accommodate any inequalities in the surface over which the 25 sleigh may pass. For this purpose the front pair of runners has been set on a king bolt and fifth wheel, and the back pair has been attached to the cross tree or body of the 30 sleigh by joints, and chains attached to the forward ends of the runners to prevent too 35 much motion. In this case the hind runner is pushed, instead of drawn along, rendering its motion uneasy, and subjecting the same to liability to become injured in passing into ruts. With this inconvenience in 40 view it has been sought to draw the hind runner along by an attachment at the forward ends and allow motion at the bolsters by means of rollers introduced at said bolsters, 45 but this device is expensive, and not readily adapted to sleigh runners already constructed, without raising the body of the sleigh sufficiently high for introducing the friction rollers and rolling bolster.

My said invention therefore does not consist 45 in attaching the forward end of the hind runner, so as to draw the same, but my said invention does consist in connecting the said runner to the cross tree of the sleigh by 50 means of a T formed slide in combination with a hinged or jointed cap on the runner or sleigh, when said runner is drawn along

by a suitable connection to its forward end, thereby a free movement is allowed to the hind runners, by a simple strong and efficient device that is applicable to sleighs already constructed, as well as to those being 55 built.

In the drawing *a*, is the front runner and *b*, the hind runner, formed in pairs of any 60 usual size or shape, and to the front runner *a*, the pole or shaft *c*, is to be attached by the usual joint (1).

d, is the bolster to the front runner under the cross tree *e*, through which the king bolt 65 2, passes to connect the parts; circles or fifth wheels might be applied at this point but I prefer that the king bolt be made with a globular head to form a universal joint and allow freedom of motion to the runner under the sleigh body. 70

f is the perch running from the front cross tree *e*, to the hind cross tree *g* and on these cross trees the sleigh body, of any desired 75 character is sustained.

h, is the draft block for the hind runner, attached to the perch *f*, and connected to the said runner *b*, by the straps *i*, or equivalent device, so as to draw said runner by its front end. It will now be apparent that as said 80 runner passes over any inequalities in the surface traveled over, the elevation or depression of the forward end of the runner involves a movement at the cross tree *g*. I therefore provide, at this point, the bolsters 85 *k*, *k*, formed of the cap pieces 3, jointed at 4, to the cross tree *g*, so as to allow for changes in the angle of the runner relatively with the body of the sleigh; and said cap pieces 3, set over and slides on the T formed pieces 90 5, that are attached on the upper side of the runner. By means of bolsters on each side, thus constructed, a free motion is allowed to the hind runner in passing over an uneven surface, at the same time that said 95 runner is securely connected to the body of the sleigh and is drawn along by a connection to its forward end.

The relative positions of the cap 3, and T piece 5 might be inverted if desired. 100

I do not claim allowing motion to the hind runner at the bolsters, said runner being drawn along by a connection at its forward end, but

What I claim as my invention and desire to secure by Letters Patent, is—

The combination of the T formed slide 5, cap 3, and joint 4, for attaching the hind runner of sleighs to the body, when said runner is drawn by a connection to its forward end substantially as and for the purposes specified.

In witness whereof, I have hereunto set my signature this fifteenth day of January 10 1858.

WM. W. ST. JOHN.
